UNITED STATES PATENT OFFICE.

LUDWIG F. C. HAAS, OF LANCASTER, PENNSYLVANIA.

SOLE-PROTECTOR FOR BOOTS AND SHOES.

1,160,162.

Specification of Letters Patent. Patented Nov. 16, 1915.

Application filed February 7, 1913. Serial No. 746,840.

To all whom it may concern:

Be it known that I, LUDWIG F. C. HAAS, a citizen of the United States, residing at Lancaster, in the county of Lancaster and State of Pennsylvania, have invented certain new and useful Improvements in Sole-Protectors for Boots and Shoes, of which the following is a specification.

The present invention relates to shoe sole protectors, and includes respective heel and toe elements, in correlation with interposed ball plates, the latter being yieldingly supported.

An object of this invention is to preserve, by suitable protection, the sole of a shoe from excessive wear, the protector including such elements which do not impede the walking of the wearer when in position.

Another object of this invention is to provide, in conjunction with the heel and toe protecting elements, interposed ball plates, the latter being yieldingly mounted in such manner as to compensate for bending of the intermediate portion of the shoe.

A further object resides in the provision of a protector of the above-mentioned type, wherein the elements referred to are quickly and easily connectible to the adjacent portions of the shoe, means of simple construction being employed for attaining a rigidity thereof when in place.

A still further object of this device is to provide a simple protector of the construction set forth above, which is highly characterized by elements of strength and lightness, the details thereof being so disposed as to obviously illustrate its durability.

With these and other objects in view, which will readily appear as the nature of the invention is better understood, the same consists in the improved construction and novel arrangement and combination of parts which will be hereinafter described and specifically pointed out in the appended claims.

In describing my invention in detail, reference will be had to the accompanying drawings wherein like characters denote like or corresponding parts throughout the several views, and in which:

Figure 1 is a side elevation of my invention, showing the same position upon a shoe

of the usual construction, the contour of the latter being illustrated in dotted lines; Fig. 2 is a bottom plan view of the protector, constructed in accordance with my invention; Fig. 3 is a detail view of the resilient connecting means between the ball plates before mentioned; and Fig. 4 is a perspective view of the resilient connecting means mentioned.

Referring now more particularly to the accompanying drawings, wherein is illustrated the preferred embodiment of my invention, the latter broadly consists of respective heel and toe protecting elements having interposed therebetween arch and ball plates, as before described. Consistent with the above, resilient connecting contrivances are employed for connection between certain elements, to compensate for bending of the shoe at certain times.

My invention more essentially consists of a heel protecting element 10, the body thereof being of the same dimensions as the under surface of the heel of an ordinary shoe. However, the same is provided with rear and side connecting plates 12 and 13, respectively, which receive suitable fastening means 14, as shown. By positioning the fastening plates, as illustrated, means are provided for attaining the complete rigidity of the heel protecting portion while in place, thus obviating danger of the same working loose, and causing discomfort to the wearer.

The forward extremity of the heel protecting member is bent to assume the position shown in Fig. 1, and provides an up-standing element 15, materially reduced in diameter or size to form an efficient pivotal mount for the arch plate presently to be described. The greatest stress is laid upon the simplicity of the heel protecting element, in view of the fact that the component portions thereof are each formed integral with the body, thus decreasing cost of manufacture to a material extent.

The pivotal mount 15, before described, is rolled at its upper extremity to form a lateral sleeve 16, which when in position lies closely adjacent other sleeves 17 on an arch plate 18. The arch plate mentioned is bent to conform with the contour of the arch por-

tion of the shoe sole, and to fit snugly there-
against in order to prevent accumulation of
dust or dirt of any kind. While the medial
portion of the arch plate is of preferably
the same diameter as the adjacent portion of
the shoe, the same is broadened at its for-
ward extremity to provide diametrically op-
posite protuberances 19. Stress is laid upon
the simplicity of the arch plate, in view
of the integral connection existing between
its component elements.

With view of pivotally connecting the
portion 15 of the heel protector and arch
plate 18, a transversely bent element 20 is
employed which is received through the
sleeves 16 and 17, respectively, as shown.
After a pin element 20' is disposed in place,
lateral movement of the component parts
will be limited. However, a vertical oscilla-
tory movement will be permitted in order to
facilitate attachment of the device to the
shoe and it will compensate for the bending
thereof at certain times.

The protuberances 19, before mentioned,
are provided at certain opposite points with
upstanding lip elements 21 which are pro-
vided at a medial point with a transverse
opening 22. Normally, the lip portions 21
extend upwardly adjacent the sides of the
shoe sole in order to prevent lateral move-
ment of the arch plate and provide mecha-
nism subsidiary to the yieldable supporting
means, before mentioned, for assuring con-
nection of the ball plates.

The toe protecting portion, before men-
tioned, consists of a body portion 23, which
is adapted to extend upwardly about the
forward portion of the toe of the shoe, a
transverse plate 24 being provided to extend
beneath and engage the shoe sole adjacent
thereto. The toe element is preferably con-
structed of a single piece of material in order
to reduce cost of manufacture, and at
the same time increase durability of the con-
nection.

The rear extremity of the toe protecting
element is provided with opposite tongues
25, which are normally in alinement with
the sides of the shoe sole, and are provided
with transverse openings 26 for reception of
the yieldable connecting elements, before
stated.

The ball plates mentioned consists of
elongated parallel aligned members 27 pro-
vided at their respective extremities with
upstanding projections 28 for engagement
with the sides of the shoe sole, as designated
in Fig. 1. The ball plates are normally
disposed between the plate 24 and arch ele-
ment mentioned. However, yieldable means
are provided for assuring connection there-
with and allowing the same to be supported in
spaced-apart relation. With a view of provid-
ing supporting means for the ball plates, the

projections 28 are provided with spaced-apart 65
apertures 29 adjacent their upper extremi-
ties, which serve to receive the said means
when in place. The yieldable supporting con-
trivances consist essentially in a metallic
resilient wire bent intermediate its ends to 70
form a coil 30, leg portions 31 extending
from the coil to provide upturned engaging
portions 32. One of the engaging portions
32 is disposed through the opening in one
of the tongue elements 25, while the other 75
engaging portions is inserted through one
of the openings 29 in the adjacent projec-
tion 28. The other connecting elements are
disposed in substantially the same manner,
and as apparent provide yieldable connect- 80
ing means which compensate for bending
of the intermediate portion of the shoe at
different times.

In order to efficiently support the connect-
ing elements and allow the same to nor- 85
mally attain a substantially vertical position,
transverse laces 33 are provided which con-
nect the coil portions 30, as illustrated.
Any form of laces may be employed with-
out in any way departing from the spirit 90
and scope of my invention.

The advantages resultant from the use of
my invention will be readily comprehended
by those conversant with the crude and un-
satisfactory devices heretofore provided in 95
this art. Such changes as are permissible
by the subjoined claims may be inserted
without departing from the spirit of my in-
vention.

Having thus fully described my invention, 100
what I claim as new and desire to secure
by Letters Patent is:—

1. A device of the character described
including a toe protecting element, a plu-
rality of ball plate members, an arch plate 105
member, and means including a plurality
of resilient members connecting the said
toe protecting element with one of the said
ball plate members and one of the said ball
plate members with the said arch plate ar- 110
ranged to permit vertical as well as longitudi-
nal movement with respect to the sole of
the shoe, as and for the purpose set forth.

2. In a sole protector for boots and shoes,
a plurality of protector plates, an upstand- 115
ing portion formed upon each plate ex-
tremity to overlap the sole of the shoe, in-
dividual coil springs connecting the adjacent
upstanding portions, and means connecting
the several springs to preclude displacement. 120

3. A device of the character described in-
cluding a toe protecting element, an arch
plate member, a plurality of ball plate mem-
bers interposed between the said toe protect-
ing element and the said arch plate, coiled 125
wire strands connecting the said toe pro-
tecting element with one of said ball plate
members and the said ball plate members

with the said arch plate, said strands permitting vertical as well as longitudinal movement of the said members with respect to the sole of the shoe, and means arranged to pass over the shoe, said means connecting the respective strands, as and for the purpose set forth.

In testimony whereof I affix my signature in presence of two witnesses.

LUDWIG F. C. HAAS.
